UNITED STATES PATENT OFFICE

HUBERT E. EWART, OF MOUNT LEBANON, PENNSYLVANIA, ASSIGNOR TO UNITED ENGINEERING & FOUNDRY COMPANY, OF PITTSBURGH, PENNSYLVANIA, A CORPORATION OF PENNSYLVANIA

WORKING ROLL BALANCE FOR A BACKED-UP ROLLING MILL

Application filed October 21, 1931. Serial No. 570,173.

This invention relates to backed-up rolling mills, and more particularly to working roll balances therefor.

In a backed-up rolling mill the metal 5 passing between the working rolls forces them against the backing rolls so that the latter are driven by the frictional contact established therebetween. However, when the mill is operating with no material being 10 rolled, there is nothing to force the working rolls, particularly the upper one, tightly against the backing rolls, which often results in there not being sufficient contact between them to enable the former to drive 15 the latter. Consequently, the backing rolls remain substantially motionless while the driven rotating working rolls grind against them and wear down their faces. This action is characteristic of three-high, four- 20 high, cluster and other backed-up mills.

It is among the objects of this invention to provide an improved working roll balance, associated with a casing in which a backing roll is journaled, for constantly 25 urging a working roll into driving contact with the backing roll, which balance can be adjusted to vary the pressure of the rolls against each other, and is adapted to facilitate removal of the working roll from 30 the mill housing.

The invention is illustrated in the accompanying drawing of which Fig. 1 is a fragmentary view, partly in cross section, of one 35 end of a rolling mill showing a working roll balance; and Fig. 2 is a sectional view taken on line II-II of Fig. 1.

Referring to the drawing, a rolling mill housing 1 is provided at its end with a window 2 in which a casing 3, having an opening 4 in its lower portion, is slidably mounted 40 for vertical adjustment by screw downs, not shown. A neck of a backing roll 5 is journaled in the casing, while a chock 6 with a working roll 7 journaled therein, is 45 slidably mounted for vertical movements in opening 4 of the casing. The working roll is thus backed-up by backing roll 5 directly above it.

To constantly urge the working roll into 50 driving contact with the backing roll when

no material is being rolled, so that the former will not slip against the latter and thereby grind their faces, there is provided a working roll balance comprising a cylindrical hollow sleeve 8 slidably disposed in a 55 chamber 9 extending upwardly into casing 3 adjacent the side of chock 6. A stud 10, screwed at its upper end in the casing, projects downwardly through the center of sleeve 8 which is provided with an inwardly-extending annular shoulder 11. Abutting 60 against the bottom of this shoulder is the upper end of a coil spring 12 held in position by means of a nut 13 threaded on the lower end of stud 10. Washers 14 and 15 are 65 inserted between the spring and shoulder, and between the spring and nut, respectively, to form end bearings for the spring.

The lower end of sleeve 8 is integrally provided with a lug 16 projecting horizontally therefrom and adapted to engage the lower face of chock 6 and support it. By turning nut 13 up on stud 10, spring 12 is compressed, which tends to force sleeve 8 upwardly in chamber 9. As the lug supports the chock, this upward movement is transmitted to the chock and the working roll journaled therein, the working roll being thereby urged upwardly into driving contact with the backing roll. To insure 70 proper engagement of lug 16 with chock 6, the latter is provided with a rabbet 17 in its lower face into which the lug projects. The proper pressure between the rolls is obtained by turning nut 13 either to the 75 right or left to compress or expand the spring. As shown, each side of each working roll may be provided with a balance constructed as explained, and it will be understood that the balances are provided at both 80 ends of working rolls.

When it is desired to remove the working roll for repair or replacement, the compressions of the springs of the several balances are released by turning their nuts 13 85 downwardly on the studs 10. This relieves the pressure on sleeves 8, thereby permitting lugs 16 to be removed from rabbets 17 so that they may be swung out of engagement with the chocks. The chocks and 90 95 100

working roll can then be pulled laterally through casings 3 without interference by the balances. There is thus provided an adjustable working roll balance of simple construction and few parts which can easily be disengaged from a working roll to permit its removal from the mill housing.

According to the provisions of the patent statutes, I have explained the principle 10 and operation of my invention, and have illustrated and described what I now consider to be its best embodiment. However, I desire to have it understood that within the scope of the appended claims, the invention 15 may be practiced otherwise than as specifically illustrated and described.

I claim:

1. In a rolling mill, the combination with 20 a housing provided with a vertically movable casing having a backing roll journalled therein, of a chock slidably mounted in said casing, a working roll journalled in said chock, and a member yieldingly connected to said casing and while thus connected movable to and completely from a position engaging said chock for urging said working roll yieldingly into driving contact with said backing roll.
2. In a rolling mill, the combination with 30 a housing provided with a vertically movable casing having a backing roll journalled therein, of a chock slidably mounted in said casing, a working roll journalled in said chock, a member rotatably mounted in said casing for movements to and from engagement with said chock, and means for yieldingly urging said member toward said working roll.
3. In a rolling mill, the combination with 40 a housing provided with a vertically movable casing having a backing roll journalled therein, of a chock slidably mounted in said casing, a working roll journalled in said chock, a sleeve mounted for angular and 45 vertical movements in said casing and provided with a lug which in one angular position of the sleeve engages said chock, and means for yieldingly connecting said sleeve to said casing for urging the working roll into driving contact with the backing roll.

50 In testimony whereof, I sign my name.
HUBERT E. EWART.

DISCLAIMER

1,898,007.—*Hubert E. Ewart, Mount Lebanon, Pa. WORKING ROLL BALANCE FOR A BACKED-UP ROLLING MILL. Patent dated February 21, 1933. Disclaimer filed March 6, 1934, by the assignee, United Engineering & Foundry Company.*

Hereby enters this disclaimer to that part of the claims in said specification which is in the following words, to wit:

“1. In a rolling mill, the combination with a housing provided with a vertically movable casing having a backing roll journalled therein, of a chock slidably mounted in said casing, a working roll journalled in said chock, and a member yieldingly connected to said casing and while thus connected movable to and completely from a position engaging said chock for urging said working roll yieldingly into driving contact with said backing roll.”

[*Official Gazette March 27, 1934.*]

working roll can then be pulled laterally through casings 3 without interference by the balances. There is thus provided an adjustable working roll balance of simple construction and few parts which can easily be disengaged from a working roll to permit its removal from the mill housing.

According to the provisions of the patent statutes, I have explained the principle 10 and operation of my invention, and have illustrated and described what I now consider to be its best embodiment. However, I desire to have it understood that within 15 the scope of the appended claims, the invention may be practiced otherwise than as specifically illustrated and described.

I claim:

1. In a rolling mill, the combination with 20 a housing provided with a vertically movable casing having a backing roll journalled therein, of a chock slidably mounted in said casing, a working roll journalled in said chock, and a member yieldingly connected to said casing and while thus connected 25 movable to and completely from a position engaging said chock for urging said working roll yieldingly into driving contact with said backing roll.
2. In a rolling mill, the combination with 30 a housing provided with a vertically movable casing having a backing roll journalled therein, of a chock slidably mounted in said casing, a working roll journalled in said chock, a member rotatably mounted in said 35 casing for movements to and from engagement with said chock, and means for yieldingly urging said member toward said working roll.
3. In a rolling mill, the combination with 40 a housing provided with a vertically movable casing having a backing roll journalled therein, of a chock slidably mounted in said casing, a working roll journalled in said chock, a sleeve mounted for angular and 45 vertical movements in said casing and provided with a lug which in one angular position of the sleeve engages said chock, and means for yieldingly connecting said sleeve to said casing for urging the working roll 50 into driving contact with the backing roll.

In testimony whereof, I sign my name.

HUBERT E. EWART.
